PLATFORM WEIGHING SCALE

Kenneth C. Allen, Dayton, Ohio, assignor to The Hobart Manufacturing Company, Troy, Ohio, a corporation of Ohio

Filed May 22, 1962, Ser. No. 70,231

Term of patent 14 years

(Cl. D52—10)

FIG-1

FIG-2

FIG-3

FIG-4

FIG. 1 is a perspective view of a platform weighing scale, showing my new design;

FIG. 2 is an elevational front view;

FIG. 3 is an elevational side view; and

FIG. 4 is a top plan view thereof.

The rear of the weighing scale is substantially flat and plain in appearance.

I claim:

The ornamental design for a platform weighing scale, substantially as shown and described.
